E. R. DRAVER

EXHAUST CUT-OUT

Filed Sept. 8, 1921

Inventor
E.R. DRAVER
By his Attorney

Michael Kilgore

UNITED STATES PATENT OFFICE.

EMIL R. DRAVER, OF RICHMOND, INDIANA.

EXHAUST CUT-OUT.

Application filed September 8, 1921. Serial No. 499,193.

My present invention relates to exhaust cut outs for automobiles or other vehicles propelled by explosive engines and has for its object to improve the same in several particulars hereinafter noted.

Generally stated, the invention consists of the novel devices and combinations of devices hereinafter disclosed and defined in the claims.

Particularly the invention is directed to an improved actuating connection for the valve acting or moveable element of a cut out device. This actuating connection includes a cable, the term "cable" being used in a broad and liberal sense to include all such devices, as, for example, wire cables, ropes, wires and chains, which are adapted to move along irregular courses and over suitably placed guides. The cable is made elastic at one or more points by a spring or springs suitably applied in or at the extremities thereof.

The actuating connection has been especially designed for moving a supplemental pipe section of an exhaust cut out such as disclosed and claimed in my prior Patent Number 1,396,410, issued of date November 8, 1921, but is capable of more general application to other types of cut out devices.

As a further important feature a cable guide is applied directly on the yoke or relatively fixed part of the cut out device so as to thereby afford a self-contained attachment in which said cable guide may be applied at the factory and will always maintain its proper position.

A second cable guide is formed on a bracket that will be supported from a suitable part of the vehicle body and to which bracket the cable is adapted to be anchored in a position to hold the valve acting cut out element in a raised position against a limiting stop at which time the spring or yielding element of the cable will be stretched or put under strain and will then serve an important purpose to be herein-after more fully described.

In the accompanying drawings which illustrate the invention like characters indicate like parts throughout the several views.

Referring to the drawings:

Fig. 1 is a side elevation with some parts sectioned and some parts broken away, illustrating the invention;

Fig. 2 is a section on the line 2—2 of Fig. 1;

Fig. 3 is a section on the line 3—3 of Fig. 1;

Fig. 4 is a side elevation illustrating a slightly modified arrangement of the cut out device; and

Fig. 5 is a perspective illustrating a still further slightly modified construction.

Describing first the construction illustrated in Figs. 1, 2, and 3, the numeral 6 indicates an exhaust pipe which has been sectioned or cut in two and its severed ends axially separated to form a gap. This gap is spanned by a rectangular yoke 7 which is open at top and bottom and provided with sleeves 8 into which the severed ends of the exhaust pipe are telescoped. The inner extremities of the sleeves 8 are preferably unbroken or complete and as shown are flush with the inner walls of the yoke 7, but the outer portions of the sleeves are partly severed by transverse slits 9 and are formed with divided or split portions having depending ears 10 through which nut-equipped bolts 11 are placed to clamp the split portions of the sleeves securely onto the sections of the exhaust pipe.

The gap formed in the exhaust pipe within the yoke 7 is adapted to be normally closed by a supplemental pipe section 12 provided with a depending elbow like exhaust deflector 13.

The valve acting parts 12 and 13 are preferably cast integral and are formed with vertically extended flanges 14 and 15 that engage the interior of the yoke 7 and hold said moveable valve acting element 12—13 against rotation while free for vertical movement. The passage through the supplemental pipe section 12 and the upper portion of the deflector 13 are closely adjacent so that they are alternately alignable with the exhaust pipe and the one will come into alignment therewith immediately after the other has been moved out of registration with said exhaust pipe. A stop lug or projection 16 on the lower portion of the deflector 13 limits the upward movement of the valve acting element 12—13 to a position in which said deflector 13 will be aligned with the exhaust pipe and the supplemental pipe section 12 will be raised above and out of registration with the exhaust pipe; and a stop lug or projection 17 on the top of the supplemental pipe section 12 limits the downward movement of said element to a position in which said supplemental pipe section will be in registration with the ex-

haust pipe and sleeves 8 and the deflector will be below said exhaust pipe and sleeves.

The cable guide on the yoke is preferably in the form of a funnel shaped head 18 formed on the laterally turned upper end of a bracket-like arm 19, the flanged base of which is rigidly secured, by machine screws 20 or the like, directly on top of the end of one of the sleeves 8. The operating cable 21 is passed through the guide head 18 and its lower end is attached to an ear 22 on the top of the supplemental pipe section 12.

The upper portion of the operating cable 21 is passed upward through an opening in the car floor 23 and is passed through another guide head 24 formed on the lower end of a guide bracket 25 which latter, by screws or otherwise, is secured to a suitable part of the car body and at its upper end is preferably formed with a forked lug 26.

As a convenient means for pulling on the cable 21 there is shown a hand piece in the form of a wire loop 27 the stem of which is bent to form shoulders 28 and 29. Below the shoulder 28 the stem of the hand piece 27 is shown as bent to form a coiled spring 30 to the lower end of which the cable 21 is directly attached. Of course, the stem of said hand piece in effect constitutes a part or continuation of the operating cable and the spring 30 gives the desired elasticity to said cable.

With the above described construction when the cable is pulled upward the valve acting element 12—13 will be raised until stop 16 engages the yoke, at which time the supplemental pipe section 12 will be above the sleeves 8 and the deflector 13 will be in position to cut the exhaust off from the muffler and to direct the same downward as shown in Fig. 1. When stop 16 is engaged with the yoke as just stated and the hand piece is pulled slightly upward the spring 30 will yield and permit the engagement of said shoulder 28 with lug 26 without requiring close adjustments and irrespective of stretch in the cable and, moreover, said spring will frictionally hold the shoulder 28 engaged with the lug 26, so that the cut out will not be accidentally dropped from its locked up position. When the said valve acting element 12—13 is thus locked up in its raised position spring 30 will exert a constant force that will hold stop lug 16 engaged with the yoke and the deflector 13 accurately aligned with the exhaust pipe. Of course, the above described stops for limiting the movements of the valve acting element of the cut out may be arranged in various different ways.

When the operating cable is released from tension the valve acting element will drop, under the action of gravity, until stop 17 engages yoke 7, at which time the supplemental pipe section 12 will register with

the exhaust pipe and sleeves 8. At such time the hand piece 27 may be supported in position where it will be easily accessible, simply by engaging its shoulder 29 with the anchoring lug 26.

The construction illustrated in Fig. 4 is substantially like that illustrated in Figs. 1 to 3, inclusive, except that the yoke 7 in this arrangement is provided with a split sleeve only at its side and at its inner side with a solid sleeve 8^a directly secured to the adjacent head of the exhaust muffler 32. In Fig. 4 the cut out is shown as lowered so that the supplemental pipe section 12 is in registration with the sleeves 8 and 8^a, thereby causing the exhaust to be delivered into the muffler. In Fig. 4 the cable 21 is shown as provided with a coiled spring 30^a not far from the guide head 18 and is provided with a normally slack portion 31 that limits the stretch or expansion of said spring.

The construction illustrated in Fig. 5 is substantially like that illustrated in Figs. 1, 2 and 3, except that the sleeves 8^b are horizontally split and formed with detachable sections 8^c, rigidly clamped to the main sleeves by nut-equipped bolts 33. In all of the above described arrangements the primary or main cable guide is rigidly attached to the yoke or fixed part of the cut out device and hence may be adjusted at the factory and the complete cut out device thereafter shipped and handled as an entirety. Of course, the latch structure will be made and handled as an independent element, but the side latch does not constitute the main part of an operative cut out. However, the elastic element in the cable is an important feature because it eliminates the necessity of close adjustments and for readjustments after the device has been in use for a considerable length of time. The spring in the cable will take up all the slack, wear and play that can occur during the life of an operating cable.

What I claim is:

1. An exhaust cut-out device comprising a valve-acting supplemental pipe section movable to open and close an exhaust pipe, an operating connection leading from said valve-acting pipe section, a relatively fixed latch element to which said connection is adapted to be anchored, and an elastic element interposed in said operating connection and arranged to be put under strain to exert tension on said operating connection when the latter is anchored to said latch element and said supplemental pipe section is in an extreme position, said operating connection having a non-elastic portion spanning the space occupied by said elastic element and limiting the elasticity thereof in one direction.

2. An exhaust cut-out device comprising a

valve-acting supplemental pipe section movable laterally into and out of a gap in an exhaust pipe to close and open the same, a flexible operating connection leading from 5 said supplemental pipe section, a relatively fixed latch element to which said connection is adapted to be anchored, a stop limiting the movement of said supplemental pipe section to an extreme position, and an elastic 10 element interposed in said flexible operating connection and arranged to be put under strain to exert tension on said operating connection and to hold said supplemental pipe section against its stop, when said connection is anchored to said fixed latch element, 15 said operating connection having a non-elastic portion spanning the space occupied by said elastic element and limiting the elasticity thereof in one direction.

20 3. An exhaust cut-out device comprising a valve-acting cut-out mounted for vertical sliding movements to open and close an exhaust pipe, a flexible operating connection leading from said valve-acting element, a 25 fixed latch element to which said operating connection is adapted to be anchored, and an elastic element interposed in said operating connection and arranged to be put under strain and to exert tension on said operating connection when the latter is anchored to 30 said latch element, said operating connection having a non-elastic portion spanning the space occupied by said elastic element and limiting the elasticity thereof in one direction.

35 4. A self-contained cut-out device comprising a yoke adapted to span a gap in an exhaust pipe, a supplemental pipe section provided with a depending deflector, movable 40 in said gap into and out of alignment with the exhaust pipe, an arm secured to said

yoke and having a guide head overlying said supplemental pipe section, an operating cable passed through said guide head and connected to said supplemental pipe section, 45 a guide bracket supported independently of said yoke and at a point distant therefrom, said bracket having a guide through which said cable is passed and said bracket having means for engaging and holding said cable. 50

5. The construction defined in claim 4 in which said cable is provided with an elastic portion.

6. A self-contained cut-out device comprising a yoke adapted to span a gap in an exhaust pipe, a supplemental pipe section movable in said gap into and out of alignment with the exhaust pipe, an operating cable extended from said supplemental pipe section, a guide for said cable, secured to 55 said yoke and overlying said supplemental pipe section, in further combination with a latch and an elastic element interposed in said operating connection.

7. A self-contained cut-out device comprising a yoke adapted to span a gap in an exhaust pipe, a supplemental pipe section movable in said gap into and out of alignment with the exhaust pipe, an operating cable extended from said supplemental pipe 60 section, a guide for said cable, secured to said yoke and overlying said supplemental pipe section, a stop for limiting the movement of said supplemental pipe section under strain from said cable, an elastic element rendering said cable elastic, and a latch to which said cable is adapted to be anchored under strain from said elastic element.

In testimony whereof I affix my signature.

EMIL R. DRAVER.
